UNITED STATES PATENT OFFICE.

GILBERT LEGH, OF KING'S LYNN, ENGLAND.

GOLF-CLUB.

1,139,985.

Specification of Letters Patent. Patented May 18, 1915.

Application filed July 5, 1913. Serial No. 777,397.

To all whom it may concern:

Be it known that I, GILBERT LEGH, a subject of the King of Great Britain, residing in King's Lynn, England, (whose post office address is The Drove House, Thornham, King's Lynn, in the county of Norfolk, England,) have invented certain new and useful Improvements in Golf-Clubs, of which the following is a specification.

10 This invention relates to golf clubs of the kind in which the head is of the "iron" type and comprises a metal blade having a thin striking face and portions extending rearwardly therefrom at the toe and heel 15 and forming the lateral boundaries of an intervening space.

It consists in improvements having for their object to increase the driving qualities of an "iron" club of the type referred 20 to while maintaining an appropriate weight and a proper distribution thereof, the rearwardly extending metal portions being disconnected and formed to taper upward from the bottom or sole of the head so as 25 to correspond in thickness at the top of the head with the thickness of the thin striking face.

A solid iron club, provided it has a sole of sufficient depth from front to rear, can 30 be converted into a club such as contemplated in the present invention by cutting away the metal at the back of the central portion of the club so as to reduce the thickness of this central portion, say to that 35 usually found in a light iron, and the cut away portion may be the same width from the sole to the upper edge or may be of varying width, for example it may increase in width from the sole toward the upper 40 edge. Further, the recess in rear of the central portion of the club head may be filled up with wood or other suitable material attached in any convenient manner to the club head, *e. g.*, by undercutting the 45 recess and dovetailing the wooden backing into the recess.

The invention is illustrated in the accompanying drawings wherein—

Figure 1 shows in rear elevation, cross section and plan view a cleek embodying the present invention; Fig. 2 shows similar views of a mashie, and Fig. 3 similar views of a modified construction of cleek.

It will be understood that the invention

may be applied to other types of clubs than 55 those illustrated.

Referring first to Fig. 1 it will be seen that the central or striking part *a* of the club head is comparatively thin, while the toe *b* and heel *c* are of thick metal along 60 the lower edge *d* tapering toward the upper edge *e* to the same thickness as the striking part *a*. There is thus at the toe and heel of the club a well defined sole from the front face to the rear face of these 65 portions, this sole being clearly shown in the cross sectional view of Fig. 1. The recess in rear of the striking face between the toe and heel may be of substantially uniform width from the lower edge to the upper edge, as shown in Fig. 1, or it may be 70 of varying width; for example as shown in the mashie illustrated in Fig. 2 it may increase in width from the lower toward the upper edge.

The improved club heads may, as shown in Fig. 2, have a slight beading or bulge *f* along the lower edge of the front face, a feature that is common to some known kinds of clubs.

The gap or recess in the rear of the striking face between the toe and heel may, as shown in Fig. 3, be filled with a block *g* of wood or other suitable material, in which case the recess is preferably undercut as 85 shown so as to retain the wooden backing which may simply be driven tightly into the undercut recess, or may be otherwise suitably secured therein.

Having thus described the nature of this 90 invention and the best means I know of carrying the same into practical effect, I claim:—

1. A metal golf club head of the kind referred to, comprising a blade having a 95 comparatively thin striking face and rearwardly extending toe and heel portions flanking a recess that is open at the top and rear, said toe and heel portions being separate one from the other and tapering upwardly from the bottom to the thickness of the striking face.

2. A metal golf club head of the kind referred to, comprising a blade having a 105 comparatively thin striking face and rearwardly extending toe and heel portions flanking a recess that is open at the top and rear, said toe and heel portions being sepa-

rate one from the other and tapering upwardly from the bottom to the thickness of the striking face and the said recess increasing in width upwardly from the bottom or sole of the head.

3. A metal golf club head of the kind referred to, comprising a blade having a comparatively thin striking face and rearwardly extending toe and heel portions
10 flanking a recess that is open at the top and rear, said toe and heel portions being separate one from the other and tapering

upwardly from the bottom to the thickness of the striking face, the said recess increasing in width upwardly from the bottom or 15 sole of the head, and a non-metal filling piece fixed in said recess.

In testimony whereof I have signed my name to this specification in the presence of two subscribing witnesses.

GILBERT LEGH.
